UNITED STATES PATENT OFFICE.

JAMES A. BROGAN, OF LAWRENCE, MASSACHUSETTS, ASSIGNOR TO UNITED SHOE
MACHINERY COMPANY, OF PATERSON, NEW JERSEY, A CORPORATION OF NEW
JERSEY.

WELT-FITTING MACHINE.

1,249,590.

Specification of Letters Patent. Patented Dec. 11, 1917.

Application filed April 7, 1916. Serial No. 89,561.

To all whom it may concern:

Be it known that I, JAMES A. BROGAN, a citizen of the United States, residing at Lawrence, in the county of Essex and State of Massachusetts, have invented certain new and useful Improvements in Welt-Fitting Machines; and I do hereby declare the following to be a full, clear, and exact description of the invention, such as will enable others skilled in the art to which it appertains to make and use the same.

This invention relates to welt fitting machines, and more particularly to machines for forming a groove and bevel on the inner edge of the welt.

In my copending application, Serial No. 797,025, filed October 24, 1914, is shown and described a machine for making a welt in which the grooved and beveled edge is formed by molding and compressing the welt and the grain face of the leather is preserved on the bevel.

The primary object of the present invention is to provide a machine of improved construction for more effectively compressing and molding a groove and bevel on the inner edge of a welt.

With this and other objects in view, the invention consists in the improved welt grooving and beveling machine hereinafter described and set forth in the claims.

The various features of the invention are illustrated in the accompanying drawings, in which—

Figure 1 is a view in side elevation of a welt grooving and beveling machine embodying the preferred form of the invention;

Fig. 2 is an enlarged view in side elevation of the upper portion of the machine illustrating the gearing for operating the various portions of the machine;

Fig. 3 is a front elevation of the machine;

Fig. 4 is a rear elevation of the machine with parts broken away;

Fig. 5 is a vertical section taken longitudinally of the machine;

Fig. 6 is a plan view of the machine showing the welt guides, the upper molding rolls being removed;

Fig. 7 is a detail view illustrating the operation of the first set of molding rolls upon the welt;

Fig. 8 is a detail view illustrating the op-

eration of the second set of molding rolls 55 upon the welt;

Fig. 9 is a detail view illustrating the operation of the third set of molding rolls upon the welt;

Fig. 10 is a perspective view of the welt 60 produced by the machine;

Fig. 11 is a vertical section of the welt moistening tank, taken on the line 11—11 of Fig. 1; and

Fig. 12 is a vertical section transversely 65 of the machine taken on the line 12—12 of Fig. 2.

In the welt grooving and beveling machine illustrated in the drawings, the welt is first conducted through a moistening liquid 70 to be tempered. It is then passed through a series of welt guides to a grooving knife, and after being grooved, is passed between three sets of molding rolls which mold and compress the groove and bevel. The welt is 75 finally conducted through a deflector which bends the welt about its grooved edge.

The moistening device (Figs. 1 and 11) consists of a tank 18 mounted upon a bracket 20 attached to the machine frame, and having a liquid inlet 22 and a liquid outlet 24 to hold the moistening liquid at a predetermined level. The welt passes in a single strand through the tank around a series of rolls 26 carried in a frame 28, which consists of a pair of side plates between which the rolls are rotatably mounted. The front end of the frame is mounted on a pivot 29 secured in the tank 18, and one of the side plates of the frame has a handle 30 by which the frame may be lifted out of the tank when threading the welt over the rolls preparatory to starting the fitting operation. The plate of the frame 28 opposite the handle 30 normally terminates substantially 90 flush with the top of the tank 18, and a spring clip 32 projects over the edge of the plate to hold the frame 28 in the tank while the welt is being drawn through the liquid.

After the welt has been moistened and tempered it passes over a roll 34 mounted in a bracket 36 which is attached to the front of the machine head 37. From the roll 34 the welt passes between an inner edge guide 38 and an outer edge guide 40 (Figs. 5, 6 105 and 12). The inner edge guide consists of a plate which is cut away to enter between the molding rolls and is adjustably mounted

upon the machine head by a series of screws 42 and slots 44. The inner edge guide engages the edge of the welt to be grooved and beveled and may be adjusted transversely of the machine to determine the position of the groove relatively to the edge of the welt. The outer edge guide 40 is a plate which has a guiding shoulder 46 to engage the outer edge of the welt, and a cover plate 48 which projects across the top or flesh side of the welt and rests upon the inner edge guide 38. The outer edge guide 40 rests upon a bottom guide 50, and the guides 40 and 50 are attached to a block 52 which is adjustable transversely of the machine head to provide for different widths of welt. The block 52 (Figs. 5 and 12) is slidably mounted on a series of intermediate driving shafts 54 and is adjusted by means of a hand screw 56 which passes through the machine head 37 and is threaded into the block. With the above construction, as the welt passes through the machine it is held between the inner edge guide 38 and the outer edge guide 40. The grain face of the welt rests upon the bottom guide 50, and the flesh face of the welt is covered by the plate 48. To facilitate threading a new strip of welt through the machine, the cover plate at the front end of the guides consists of a hinge 58 (Fig. 6), one plate of which is fixed on the guide 38, and the other plate of which swings across the top of the welt and rests upon the top of the bottom guide 50. The movable section of the hinge is normally held in a position to uncover the welt by means of a spring 60, and is held down upon the welt during the grooving operation by means of a latch 62 which is pivoted to the machine head 37.

The deflector for bending the welt toward the grooved edge after it has been grooved and beveled consists of a curved guiding face 64 formed on the outer edge guide 40 and a curved guiding face 66 on the inner edge guide 38. As the welt emerges through the guides 64 and 66 it is bent toward the grooved edge, and since it is in a moist temper it will readily respond to the bending and retain its deflected shape. To hold the welt between the guides 64 and 66 a plate 68 is loosely hinged between the guides and rests on the top of the welt.

In order that the groove and bevel may be formed in the starting end of the welt, a preliminary feed roll 70 is placed immediately in advance of the grooving knife to feed and position the welt before it reaches the grooving knife. The feed roll 70 is mounted upon a shaft 72 which is journaled in a carrier 74. The carrier 74 is pivotally mounted in the end of a floating arm 76 upon a shaft 78. The arm 76 is loosely pivoted in a bracket 77 which is attached to the front of the machine head so that the feed

roll 70 may move toward and away from the welt. The feed roll 70 is yieldingly held upon the welt by means of a spring 80 (Figs. 1 and 2) which is connected between a turn buckle 82 mounted in the bracket 20 and a strap 84 which engages the carrier 74. The feed roll is positively driven by means of gears 86 and 88 mounted on the shafts 72 and 78 respectively, the gear 88 meshing with a gear 90 on a shaft 92 mounted in the arm 76, and a driving gear 94 fixed to the gear 90 and meshing with a gear 96 on one of the intermediate driving shafts 54. With this construction the feed roll has a freedom of movement toward and away from the welt during the feeding operation. To give the feed roll an effective bite on the welt, a bearing roll 98 is mounted in the bottom guide 50 immediately below the feed roll (Fig. 5). A series of feed teeth 100 are formed on the roll 70, which penetrate the welt to prevent the welt from being moved away from the inner edge guide 38. In this way the inner edge of the welt will be securely held against the guide 38 while it is being acted upon by the grooving knife.

The preliminary feed roll advances the welt to a grooving knife 102 which is held in a knife carrier 104 adjustably mounted on a movable section 106 of the machine head (Figs. 1, 2 and 5). The knife 102 is secured in position in the carrier by means of a screw 108, and a gage 110 is pivoted to the side of the carrier, which may be swung down in front of the carrier to accurately set the cutting edge of the knife. The knife carrier 104 has a deflecting face 112 which deflects the shavings from the knife over to a chute 114 arranged to discharge toward the base of the machine. A shield 116 is mounted in front of the knife which aids in guiding the shavings down through the chute 114. The knife carrier is adjustable toward and from the welt to vary the depth of groove, by means of a thumb screw 118 which is fixed in a bracket 120 attached to the machine head 106, and is threaded into the upper end of the carrier 104. The adjusted position of the carrier is maintained by means of a set screw 122 which works in a slot 124 formed in the carrier. The knife carrier may be adjusted transversely of the machine (Fig. 3) by means of a hand screw 126 which is mounted in the machine head 106 and is threaded into a shank formed in the bracket 120. The adjusted position of the bracket 120 is maintained by means of set screws 128 which are mounted in the machine head and pass through slots 130 in the bracket. To provide a bearing for the knife to cut against, a roll 132 is mounted on a preliminary driving shaft 54 immediately under the cutting edge of the knife.

After the welt has been grooved, it is conducted between three sets of molding rolls

which are shaped to progressively compress the material of the groove and form a bead and bevel on the grain side of the welt opposite the groove. The upper molding rolls 5 which contact the flesh side of the welt are pinned to the upper molding shafts 134 which are journaled in the movable section 106 of the machine head. The lower molding rolls which contact the grain face of the 10 leather are pinned to the lower molding shafts 136 which are journaled in the machine head 37. 15

Viewing Fig. 7, the upper molding roll 138 of the first set has a peripheral rib 140 which is shaped to compress the side of the groove toward the outer edge of the welt. The lower molding roll 142 has a peripheral groove 143 semi-circular in shape, immediately opposite the rib 140, to assist in preliminarily forming the bead 144 on the grain 20 side of the welt. The rolls 138 and 142 assist in feeding the welt, and the upper molding roll has a series of feeding teeth 145 which pierce the flesh side of the welt and form a series of indentations 146 on the flesh side. The feed teeth 144 act to hold the inner edge of the welt from movement away 25 from the inner edge guide 38. 30

Viewing Fig. 8, the upper roll 147 of the second set of molding rolls has a peripheral rib 148 which is substantially V-shaped and acts in forming both sides of the groove. The lower molding roll 150 has a peripheral groove 152 opposite the rib 148, and this groove is shaped to preliminarily form the bevel 153 on the welt. The rolls 146 and 150 also act to feed the welt, and a series of feed teeth 154 are formed on the roll 146 similar to the feed teeth 145 on the roll 138. 40

Viewing Fig. 9, the upper molding roll 156 of the third set of molding rolls has a peripheral rib 158 which has a shape opposite the shape of the rib 140, and acts on the side of the groove adjacent the inner edge 45 of the welt. The lower molding roll 160 has a peripheral groove 162 opposite the rib 158, and this groove is shaped to give the final shape to the bead and bevel of the welt on the grain side. The rolls 156 and 160 also 50 act to feed the welt, and a series of feed teeth 164 are formed on the roll 156, similar to the teeth 145 on the roll 138, to place indentations on the flesh side of the welt. 55

As shown in Figs. 7, 8 and 9, the feed teeth 145, 154 and 164 project different distances from the face of the rolls 138, 147 and 156 respectively, and these act to progressively enlarge and deepen the indentations 146 placed upon the flesh side of the welt. The 60 ribs and grooves on the molding rolls tend to stretch or lengthen the inner edge of the welt, and the teeth on the molding rolls act to stretch or lengthen the outer edge of the welt to counteract the lengthening of the inner edge, so that as the welt enters the de- 65

flector it has a tendency to bend toward the inner edge of the welt. During the compressing operation the welt is in a moistened and tempered condition, so that the shape imparted is permanently retained by the 70 welt. 75

The feed teeth on the upper molding rolls prevent edgewise movement of the welt while the groove and bevel are being formed, and a series of presser feet 165 (Fig. 6) 75 mounted in the outer edge guide 40 between the molding rolls, hold the inner edge against the inner edge guide 38 as it enters the bite of the molding rolls. The presser feet 165 are pivoted to the guide 40 and are 80 yieldingly held in engagement with the outer edge of the welt by means of leaf springs 166 which are attached to the guide 40 and bear against the free ends of the presser feet. 85

To give access to the molding rolls and grooving knife, the movable portion 106 of the machine head is pivoted to the main portion of the machine head 37 by a hinge 168 (Figs. 6 and 12) and can be swung up 90 away from the welt guides. During the normal operation of the machine the pivoted head 106 is positioned relatively to the main portion of the machine head by means of a link 170 (Figs. 1, 2, 3, 4 and 12) which 95 is connected between a bracket 172 on the machine head 37 and a bracket 174 on the movable section of the machine head 106. When the movable section is to be moved away from the main section of the machine 100 head, a pin 176 is removed from the bracket 172 to free the link 170. To adapt the machine for placing different pressures on the various kinds of welt while forming the groove and bevel, an adjusting bolt 178 connects the upper end of the link 170 with the bracket 174, and an eccentric portion 180 of the bolt passes through the link 170. The adjusting bolt 178 has a series of graduations 182 on its head (Fig. 3) which move 110 under a pointer 184 on the bracket 174 to indicate the positions of the machine head 106 for different pressures on the welt. 105

The power for driving the feeding rolls and the molding rolls is derived from a 115 power belt 186 (Figs. 2 and 3) which is shifted back and forth between a loose pulley 188 and a tight pulley 190 on the main driving shaft 192. A gear 194 on the main driving shaft 192 meshes with gears 196 on 120 the shafts 136 carrying the lower molding rolls 142 and 150. An intermediate gear 198 on an intermediate driving shaft 54 to the left of the driving shaft 192, Fig. 2, meshes with the gear 196 on the shaft 136 125 of the lower molding roll 150 and a gear 196 on the shaft 136 of the lower molding roll 160. An intermediate gear 200 on an intermediate driving shaft 54 at the right of the driving shaft 192, meshes with the gear 130

196 on the shaft 136 of the lower molding roll 142 and a gear 202 on an intermediate driving shaft 54. A gear 204 on a lower intermediate driving shaft 54 meshes with the gear 202 and a gear 206 on the shaft 54 which carries the gear 96 that drives the preliminary feed roll 70. A series of gears 208 are mounted on the shafts 134 carrying the upper molding rolls, and the gears 208 mesh with the gears 196 which drive the lower molding rolls.

The bead formed on the grain side of the welt assists materially in forming the bevel and giving the proper shape to the inner edge of the welt to fit into the shoulder formed in the upper into which the welt is attached. By enlarging or exaggerating the bead it can be formed to imitate a cork sole. With the improved welt the grain 15 face of the leather is preserved on the bevel so that the groove can be placed close to the inner edge and thus a narrower welt can be used for the same kind of shoe making than was heretofore possible. The grain 20 face of the welt is the stronger portion, and since the groove is consolidated and compressed, the stitch receiving portion of the welt is strengthened by the operation of the improved machine. The welt is moistened 25 before being operated upon, and can be easily molded and compressed into the desired shape, and when it has been treated in the machine it will retain the molded 30 shape. The rounded beveled edge of the 35 welt as formed in the improved machine is substantially the shape which the welt assumes when it is attached to the upper and insole so that the inseam can be drawn in tightly and there is no tendency for the 40 inseam to close up the groove during the inseam sewing operation. The indentations on the upper face of the welt form pockets 45 for the cement and give an excellent surface to which the outsole may be attached by cement.

The welt herein disclosed forms the subject-matter of my co-pending application Serial No. 47,518, filed August 26, 1915.

The preferred form of the invention having been thus described, what is claimed as new is:—

1. A welt fitting machine, having, in combination, a knife for grooving the flesh side of the welt near its inner edge, and means 55 for compressing and molding the grooved edge of the welt to form a bevel and bead on the grain side of the welt.

2. A welt fitting machine, having, in combination, a knife for grooving the flesh side 60 of the welt near its inner edge, and a pair of coöperating rolls for compressing and molding the grooved edge of the welt to form a bevel and bead on the grain side of the welt.

65 3. A welt fitting machine, having, in com-

bination, a knife for grooving the flesh side of the welt near its inner edge, means for compressing and molding the grooved edge of the welt to form a bevel on the grain side of the welt, and mechanism for placing a series of indentations on the flesh side of the welt to roughen its under face and lengthen the outer edge. 70

4. A welt fitting machine, having, in combination, a knife for grooving the flesh side 75 of the welt near its inner edge, and a series of pairs of coöperating rolls for compressing and molding the grooved edge of the welt to progressively form a bevel and bead on the grain side of the welt. 80

5. A welt fitting machine, having, in combination, a knife for grooving the flesh side of the welt near its inner edge, a pair of coöperating rolls to engage the opposite sides of the welt for compressing and molding 85 the grooved edge of the welt, and a series of feeding teeth on the roll engaging the flesh side of the welt to roughen the face of the welt and lengthen the outer edge. 90

6. A welt fitting machine, having, in combination, a guide for the inner edge of the 95 welt, a knife for grooving the welt, means for compressing and molding the grooved edge of the welt to consolidate the groove and form a bevel, and a plurality of feed rolls having teeth to hold the welt from edge-wise movement while it is being grooved and beveled. 100

7. A welt fitting machine, having, in combination, a guide for the inner edge of the 100 welt, a knife for grooving the inner edge of the welt, means for compressing and molding the grooved edge of the welt to consolidate the groove and form a bevel, and a feed roll in advance of the knife to yieldingly 105 engage the welt. 105

8. A welt fitting machine, having, in combination, a knife for grooving the welt, a pair of coöperating compressing and molding rolls to compress the groove and form 110 a bevel on the welt opposite the groove, a guide for the grooved edge of the welt which is adjustable to vary the distance of the groove from the edge of the welt, and means for holding the welt against the guide. 115

9. A welt fitting machine, having, in combination, a knife for grooving the flesh side of the welt near its inner edge, and molding and compressing rolls for engaging opposite sides of the welt, the roll in engagement with the grooved side having a rib to compress and consolidate the groove and the roll in engagement with the grain side of the welt, having a peripheral groove to compress and mold a bead and bevel on the inner edge of the welt opposite the groove. 120 125

10. A welt fitting machine, having, in combination, a knife for grooving the welt, a plurality of pairs of rolls for molding and compressing the welt, and a series of teeth 130

on each pair of rolls to engage the grooved face of the welt to place indentations in the welt, the teeth of the succeeding rolls being of different lengths to progressively enlarge the indentations.

11. A welt fitting machine, having, in combination, a moistener having guides to conduct a single strand of welt through a moistening liquid, a welt guide, a knife for grooving the welt, and a plurality of rolls to compress and mold a bevel and bead on the moistened grooved edge of the welt.

12. A welt fitting machine, having, in combination, a grooving knife, a carrier for the knife, a deflector formed on the carrier near the cutting point to carry the shavings away from the work, and a plurality of coöperating rolls for compressing and molding a bevel on the grooved edge of the welt.

13. A welt fitting machine, having, in combination, means for cutting one face of the welt near an edge, and a series of pairs of coöperating rolls for compressing and molding the cut edge of the welt to form a groove

and bevel, each pair of said rolls being arranged to form different parts of the groove and bevel.

14. A welt fitting machine, having, in combination, a grooving knife to groove one side of the welt at its inner edge, and a series of pairs of rolls for compressing and molding the welt to form a bead and bevel opposite the groove, one roll of each of said pairs having a rib to engage the groove of the welt, and the other roll of said pairs having a peripheral groove located opposite the rib on the first rolls, said ribs and grooves on the different sets of rolls being arranged to operate on different portions of the bead and bevel.

15. A welt fitting machine, having, in combination, means for feeding the welt, a grooving knife, a carrier for the knife, and a gage pivoted on said carrier and movable into and out of position to determine the setting of the cutting edge of the knife.

JAMES A. BROGAN.
